COMB CLEANER EMBODYING A CASING AND SPRING RETRACTED FLEXIBLE ELEMENT

Frederick E. Hummel, Chicago, Ill.

Application January 7, 1948, Serial No. 992

2 Claims. (Cl. 132—29)

1

This invention relates to a device for cleaning combs and has for its primary object to provide an inexpensive compact unit well adapted to serve its intended purpose and having strong appeal as a novelty, in addition to being highly efficient in operation.

In the drawings which accompany this specification:

Fig. 1 is a perspective exterior view of a comb-cleaning kit embodying my invention;

Fig. 2 is a longitudinal sectional view thereof;

Fig. 3 is a transverse section taken at line 3—3 of Fig. 2; and

Fig. 4 is a transverse section taken at line 4—4 of Fig. 2.

Fig. 5 is a detail view of a bearing member.

The comb cleaner illustrated in Figs. 1—4 comprises a housing 10 which may be a tube of indurated fibre, plastic or metal or any other appropriate material of sufficient toughness and rigidity.

Mounted within housing 10 and co-axial therewith is a shaft 11 which is journaled in bearings 12, consisting each of a length of stiff spring wire formed to provide a central loop 13, the eye of which is proportioned to receive one end of the shaft 11. In order that the latter may be restrained against inordinate lengthwise displacement, it is reduced in diameter at the bearing areas to form grooves which afford thrust shoulders at either side of the loops 13. With this construction it is necessary either to form loops 13 with the shaft 11 in place or to twist the bearing members so as to open the loops for insertion of the shaft. If the bearing members 12 are made of suitably tempered wire, the loops can be sufficiently opened for insertion of the shaft without distorting the wire beyond the elastic limit.

The two end portions of bearing members 12 are bent to form shoulders at 14 which fit accurately within the bore of housing 10 so as to properly center shaft 11, and also form lugs 15 which project through small apertures in housing 10 and thereby function to secure the bearing members in place. The overall length of each bearing member 12 should be only a little greater than the bore diameter of housing 10 so that said bearing members can be pushed into place from the open ends of the housing without excessive distortion.

A torsion spring 16 encircles shaft 11 and is attached thereto at one end while its other end is anchored to the adjacent bearing member 12. Rotation of the shaft serves to twist said spring which, upon being so twisted, stores up energy to,

2

in turn, rotate the shaft back to its normal position of rotation.

A web 18 consists of a series of laterally spaced threads or strings which are adapted to enter individually the interstices between adjacent teeth of a comb and is capable of being manipulated in a manner effective to dislodge any accumulation of detritus between the teeth. The web 18 is provided with a rod or dowel 19 at its outer end and, of course, is attached at its inner end to shaft 11. The ends of said web preferably are woven to form a substantial fabric consisting of warp and woof. This facilitates attaching the web to the shaft and to rod 19.

Means for mounting and supporting a comb exteriorly of the housing in a position to be operated upon by the strings or threads forming web 18, comprise two hook-like brackets 22, 22 attached to the outside of the housing and adapted to form rests for the back edge of the comb. The comb is indicated in dot-dash outline in Fig. 3 and identified by reference numeral 23.

Telescoped into each end of tubular housing 10 are two metal cup-like plugs 24. These are held in place frictionally, and each has a slot-like opening 25 (see Fig. 4) which registers with a similar opening 26 in the housing. Brackets 27, each welded or otherwise secured to the inner surface of one of the plugs 24, each forms an anchorage for a spring steel strip 28, which is wound spirally about said bracket and extends through the openings 25 and 26. Said spring steel strips are bent at their outer ends to form hooks 29 which are adapted to embrace the free ends of the comb teeth, as best illustrated in Figs. 1 and 3. The two strips 28 are tensioned inwardly, which is to say in the direction tending to draw them into the position depicted in Fig. 4. Thus, when said strips are engaged with a comb, as shown in Fig. 1, they serve to press the comb against the brackets 22 and thereby hold the same in place.

With the comb clamped in position, as shown, the web 18 is drawn out of the housing sufficiently to enable the strings or threads thereof to be moved laterally into the interstices of the comb teeth. The web is then moved back and forth and in and out, as indicated by the directional arrows on Fig. 3, with the result that the detritus is completely dislodged.

While I have shown for purposes of illustration only one embodiment of my invention, it will be apparent that the invention is susceptible of numerous modifications within the scope and spirit of my inventive concept, and I do not wish to be

limited save as indicated by the terms of the appended claims.

Having described my invention, what I claim as new and wish to secure by Letters Patent is:

1. A comb-cleaning device comprising: a tubular housing, bracket means secured to the exterior of said housing for mounting a comb thereon in position to be cleaned, a pair of inserts forming removable closures for the respective ends of said housing, a pair of spirally wound flat springs, each anchored at one end to one of said inserts and having a free end portion extending outwardly of the housing, each said free end portion being bent to form a hook adapted to engage and bear endwise against the teeth of a comb mounted on said bracket means in such manner as to clamp the comb in the aforementioned position, a rotatable shaft disposed within and extending lengthwise of said housing, an elongate web secured at one end to said shaft and wound thereon, the free end of said web passing through a slot in said housing to the exterior thereof, said web comprising a plurality of laterally spaced threads or strings extending lengthwise of the web and adapted to enter the interstices of the comb teeth, a retracting spring connected to said shaft, said web being operative to rotate said shaft in one direction upon being withdrawn from the housing, the rotation of said shaft in said one direction being effective to tension said spring, said spring being operative by reason of said tensioning to rotate said shaft in the opposite direction and thereby draw said web back into the housing.

2. A comb-cleaning device comprising, in combination: a tubular housing, a pair of brackets secured to the exterior of said housing for mounting a comb thereon in position for cleaning, a pair of inserts forming removable closures for the respective ends of said housing, a pair of spirally wound flat springs, each anchored at one

end to one of said inserts and having a hooked free end portion extending outwardly of the housing, said hooked end portions being adapted to engage and bear endwise against the teeth of a comb mounted on said brackets, in such manner as to clamp the comb in the aforementioned position, a rotatable shaft disposed within and extending lengthwise of said housing, an elongate web secured at one end to said shaft and wound thereon, the free end of said web passing through a slot in said housing to the exterior thereof, said web comprising a plurality of laterally spaced threads or strings extending lengthwise of the web and adapted to enter the interstices of the comb teeth, a helical retracting spring encircling said shaft and connected thereto at one end, said web being operative to rotate said shaft in one direction upon being withdrawn from the housing, the rotation of said shaft in said one direction being effective to wind said spring, said spring being operative by reason of said winding to rotate said shaft in the opposite direction and thereby draw said web into the housing.
